MULTIFACED SIGN

Filed Jan. 31, 1923

UNITED STATES PATENT OFFICE.

FRANK L. PRIEST, OF ST. LOUIS, MISSOURI.

MULTIFACED SIGN.

Application filed January 31, 1923. Serial No. 616,037.

My invention relates to improvements in multi-faced signs, and more particularly to signs having at least two legends comprising characters within whose outlines are resident 5 illuminants bearing such relation to the two legends as to be directly exposed in the bodies of the characters of both legends, to the end that the various characters, although of contours differing in the two legends, present a 10 like effect and include directly exposed illuminants common to the characters of both legends.

My object is to provide a sign comprising a bank, or group, of illuminants, such as incandescent electric lamps and opposed legend bearing elements, whose various characters, or fragments of characters, are so related to the illuminants as to directly expose the illuminants within the bodies of the characters of 20 both legends to the end that both legends will present the same general appearance and the installation and operating expense of the illuminants be minimized.

A further object is to provide a sign of the 25 character designated, having simple means for the facile interchangeability of the legend forming characters.

A still further object is to provide a sign having interchangeable legend bearing elements 30 with simple means for adapting the grouping, or arrangement, of the illuminants to conform with various of the characters of the recited changeable legend bearing elements.

My improvements consist in the novel construction, arrangement and combination of elements, as will be hereinafter clearly, fully and concisely described, definitely pointed out in my claims and illustrated by the accompanying drawing, in which:

Fig. 1 is an elevation, or face view, of a sign, 40 constructed in accordance with my invention, bearing the legend E, showing exposed lamps in the body of the legend and by dotted lines certain lamps of the same bank for exposure in the body of an opposed legend.

Fig. 2 is a transverse sectional elevation taken on the line indicated 2—2 of Fig. 1.

Fig. 3 is a sectional plan view taken on the line indicated 3—3 of Fig. 1.

Fig. 4 is a sectional plan view taken on the line indicated 4—4 of Fig. 1, and

Fig. 5 is a perspective view of the sign shown in Fig. 1.

Referring by numerals to the drawing, 6 55 designates the framing, or support, for the sign, which, in the form shown, comprises a

pair of oppositely faced channel irons in vertical disposition and relatively spaced laterally.

Secured between the channel irons of the support 6, as by the brackets 7, is a frame 8, preferably made of channel iron, and disposed with relation to the channel of the support 6 so that sectionally the frame 8 and support 6 form a conduit, such as 9, for wiring, and carried by this frame is a plurality of sockets 10 for electric incandescent lamps 11.

By preference and for uniform and economical production, the frames are made rectangular and of both height and width dimensions in excess of the height and width dimensions of the legend characters, whereby the lamp filaments may reside in the bodies of the legend characters. By further preference, the sockets 10 are so disposed as to support the 75 lamps 11 with their filaments, all resident in a plane at the midsection of the frame and with their axes at right angles, or substantially so, to the line of sight.

Over opposite sides of the frame 8 are the 80 legend bearing elements 12 and 13, preferably of sheet form and made of sheet metal and provided each with flanges 14 which overlie the outer flat faces of the supports 6, secured against vertical movement, as by screws 15, 85 and relatively secured, as by the snap-latches 16, as best shown in Fig. 3.

As shown, the legend consists of the gothic E formed as a trough, or depression, in the element 12, whose bottom 17 reaches a plane at 90 the midsection of the two legend bearing elements, as shown in Figs. 2, 3 and 4, and has formed therethrough openings 18 for the accommodation of the lamps 11, and in whose side walls 19 there are openings 20 for the extension of the lamp plugs to the various sockets 10.

In the visible side of the sign shown in Fig. 1, the lamps A, B, C and D reside in the stem of the legend E; the lamps E and F reside in the upper horizontal bar of the E; the lamps G and H reside in the lower horizontal bar, and the lamp I resides in the middle bar of the E.

In circuit with the bank of lamps A B, C, D, E, F, G, H, and I, just recited, there are lamps J and K, which are not visible as viewed from the sign side shown in Fig. 1.

The sectional Figs. 2, 3 and 4, show a sign having the legend E visible from both sides; 110 that is, both elements 12 and 13 bear the legend E, having like appearance, but, of course,

the legend in the element 13 is negative to the legend in the element 12. The stem of the legend in the element 13 intersects the lamps J, K, F and H; its upper bar intersects lamps 5 E and A, and its middle bar intersects lamp I, and its lower bar intersects lamps G and D.

By this arrangement of eleven lamps two legends E of identical appearance are equally illuminated and include within their outlines 10 an equal number of directly exposed lamps.

Thus there are nine exposed lamps in each legend whereas in the double faced signs of other designs, where the lamps are directly 15 exposed, each legend would of necessity require nine lamps, or eighteen lamps be required for the two legends E.

Obviously the frame 8 and the arrangement of the bank of lamps, A, B, C, D, E, 20 F, G, H, J and K, without alteration or addition thereto may be employed for the gothic legends C, D, J, L, O and U, and it will be obvious, further, that the same bank as shown in the legend E, including the lamp 25 I, without change, may be employed in the gothic legends A, B, C, D, F, G, H, I, J, L, O, P, R, S, T and U. In such of the legends as the gothic K, M, N, Q, V, W, X, Y and Z, wherein certain fragments of the characters 30 would not register with a superimposed character of any opposed legend, special arrangement of lamps is provided by the brackets, such as the one 21, shown in Fig. 1, which may be varied as to shape or dimension 35 and secured where necessary to the frame 8.

The supports 6 may be of lengths to include several of the units, as just described in detail, to the end that a number of such 40 units, each bearing a character, on each sign face, may be supported in arrangement to be combined in a single legend, such as one including a number of the letters of the alphabet for vertical or horizontal reading.

45 In order to present a "finished" appearance, the uppermost margins of each unit are offset inwardly, as shown at 22, in Fig. 2, to receive thereover the lower margin of another unit, such as the crown unit 23 shown.

50 I claim:

1. In a sign of the character described, opposed legend bearing elements each having an opening through a portion of its legend, the openings being arranged in alinement, and an illuminant disposed in alinement 55 with, and directly exposed by the opening in each of the elements, whereby a portion of each legend is lighted, directly, by said illuminant.

60 2. In the sign of the character described, opposed legend bearing elements, having registering openings therethrough intersecting the characters of the legends and illuminants resident in said openings, and directly exposed in the characters of both legends.

3. In a sign of the character described, opposed legend bearing elements, a plurality of illuminants resident in the plane of the midsection of the two legend bearing elements, there being openings in said elements 70 within the outlines of the characters of their legends whereby each illuminant is directly exposed in either or both of the legend characters.

4. In a double faced sign, a pair of opposed legend bearing elements, depressions forming legend characters in said elements, there being openings formed through said elements intersecting said depressions and a single set, or bank, of illuminants for direct 75 exposure in said openings.

5. In a double faced sign, a pair of opposed legend bearing elements, depressions forming legend characters in said elements, there being openings formed through said 85 elements intersecting said depressions and a single set, or bank, of illuminants for direct exposure in said openings, certain portions of said depressions in the two elements being out of register and certain of said openings being out of register so that certain of 90 said illuminants will be exposed in one legend character and obscured in the opposed legend bearing element.

6. In a sign of the class described, a pair 95 of opposed legend bearing elements, a trough-shaped depression in each element, a plurality of electric lamps supported between said elements, and there being openings in said elements intersecting said depressions whereby said lamps are exposed 100 where desired in said depressions.

7. In a sign of the character described, interchangeable pairs of opposed legend bearing elements, each having a trough-shaped 105 depression outlining the legends, a plurality of electric lamps supported between said elements, there being openings in said elements intersecting said depressions, certain of which openings register in the two elements 110 whereby to directly expose the same lamp in both legends and certain other of which openings are arranged out of register to expose certain other single lamps in a selected legend only.

8. In a sign of the character described, interchangeable pairs of opposed legend bearing elements, each having a trough-shaped depression outlining the legends, a plurality 115 of electric lamps supported between said elements, there being openings in said elements intersecting said depressions, certain of which openings register in the two elements whereby to directly expose the same lamp in both legends and certain other of which openings 120 are arranged out of register to expose certain other single lamps in a selected legend only, and means whereby the positions of certain lamps may be varied as required.

9. A sign comprising opposed elements 130

forming distinct legends having openings therethrough, and an illuminant disposed to occupy portions of the opposed openings, and visible as a part of the several legends.

5 10. A sign comprising apertured legend bearing elements, an illuminant disposed in a plane common to the several elements, and resident in the openings in the several legends, and an illuminant arranged for direct exposure in one only of the several legends.

11. A sign comprising opposed elements forming depressed legends, a plurality of illuminants and means forming openings therefor in the legends, whereby certain of the illuminants form corporate parts of distinct legends, and are directly visible from each side of the sign.

12. A sign of the character described, comprising opposed elements having depressed legends therein, and having registering openings through the legends, and an illuminant

between the elements, identically visible, through the registering openings, with respect to opposed legends.

13. A sign of the character described, comprising opposed, depressed legends having registering openings therein for the reception of an illuminant whereby the illuminant may be directly exposed in both legends.

14. A sign comprising opposed contiguous elements having depressed legends therein and provided with openings in said legends, and an electric bulb disposed in a plane common to both of said elements, and resident in said openings.

15. A sign comprising an illuminant, and elements each bearing a distinct legend depressed from a plane surface toward the illuminant, which is common to said legends, and visible in each.

FRANK L. PRIEST.
